FRANK SMITH AND JAMES T. CLABBY, OF TROY, NEW YORK.

NON-REFILLABLE BOTTLE.

1,036,158.

Specification of Letters Patent. Patented Aug. 20, 1912.

Application filed February 26, 1912. Serial No. 679,954.

To all whom it may concern:

Be it known that we, FRANK SMITH and JAMES T. CLABBY, each a citizen of the United States, residing at Troy, county of 5 Rensselaer, and State of New York, have invented certain new and useful Improvements in Non-Refillable Bottles, of which the following is a specification.

The invention relates to such improvements and consists of the novel construction and combination of parts hereinafter described and subsequently claimed.

Reference may be had to the accompanying drawings, and the reference characters 15 marked thereon, which form a part of this specification. Similar characters refer to similar parts in the several figures therein.

Figure 1 of the drawings is a central, vertical section of a non-refillable bottle embodying our invention. Fig. 2 is a view in perspective of the cage-holder. Fig. 3 is a view in perspective of the cage. Fig. 4 is a view in perspective of the screen-tube. Fig. 5 is a view in perspective of the locking 25 washer.

The principal object of the invention is to practically prevent by a simple and inexpensive mechanism the refilling of bottles, and to insure the detection of any serious 30 attempt to tamper with said mechanism.

Referring to the drawings wherein the invention is shown in preferred form, 1, represents the body of the bottle having a convergent shoulder-portion, 2, leading to a 35 neck-opening, 3, adapted to be closed by a valve, 4, shown in the form of a ball, and preferably made hollow, or of some material which will float in the liquid which the bottle is adapted to contain. The valve, 4, seats 40 upon the inner surface of the neck of the bottle at the lower end of the valve-chamber, 5, shown as an enlargement of the neck, and is held to its seat by a weight, 6, connected with the valve by a rod, 7, which has 45 a universal swivel-connection with the valve at 8.

The walls of the valve-chamber, 5, converge downward to the valve-seat, and converge upward to a seat, 9, against which 50 rests the cage-holder, which comprises a circular hollow body, 10, with a hollow stem, 11, extending upward therefrom. The outer end of the hollow stem is closed at, 12, and the stem is formed with lateral outlets, 13. 55 The hollow body, 10, of the cage-holder is formed with undercut walls as shown in

Fig. 1, adapted to be frictionally engaged by a pair of resilient tongues, 14, on the cage-holder, 15, which is inserted and frictionally held within the cage-holder. The 60 cage, 15, is also formed with inwardly bent tongues, 16, which provide openings, 17, for the passage of liquid into the cage from the valve-chamber. The cage contains a screen-tube, 18, extending from the bottom of the 65 cage up into the stem, 11, said screen-tube being made of wire-netting. The cage-holder is sealed in position by means of a tapered washer, 20, through which the stem, 11, passes, and a body of cement, 21, which 70 fills the space between said washer and the neck of the bottle.

The neck of the bottle is shown formed with an interior annular groove, 22, and the washer, 20, with an exterior annular groove, 75 23, into both of which grooves the cement enters, so that when the cement hardens the parts are irremovably locked in position, and thus retain the cage-holder in position. The outer neck of the bottle is made of a 80 sufficient internal diameter to permit the cage-holder, 10, to be freely inserted therethrough to its seat 9.

In closing the bottle, the valve, 4, with its connected weight, 6, is first inserted 85 through the neck, then the cage-holder, with the cage, 15, and screen-tube, 18, inserted therein, is inserted through the neck of the bottle until the cage-holder engages the seat 9. A quantity of cement is then distributed 90 around the grooved portion, 22, of the neck of the bottle, and the washer, 20, is forced down through the body of cement until it engages the top of the cage-holder 10. In reaching this position the washer, 20, causes 95 the cement to spread and be forced into the respective grooves, 22, and 23.

The cage, 15, is normally retained by the holder, 10, at a sufficient distance from the valve, 4, to permit free movement of the 100 valve within the valve-chamber, 5, when the bottle is sufficiently inverted to relieve the valve from the pull of the weight, 6; and the dimensions of the cage are such that should it be displaced from the holder, 10, 105 the cage would substantially fill the valve-chamber, as indicated by dotted lines in Fig. 1, and prevent the opening of the valve, 4, even though the bottle be fully inverted.

The tongues, 14, being resilient, tend to 110 open out or spread as soon as relieved from the confining influence of the holder, 10, so

that, should the cage be forced down out of the holder, the spreading of said tongues would absolutely prevent the return of the cage into the holder without obtaining access to the parts by breaking the bottle.

5 The screen-tube, 18, renders it difficult to insert any sort of a tool or wire through the devious passageway necessary to obtain access to the valve, 4, by passing through one 10 of the apertures, 13, the stem, 11, and one of the apertures, 17, in the cage; but, should a more serious effort be made to obtain access to the valve, the cage, 15, which is retained merely by the frictional hold of the tongues, 15, 14, will be forced down out of the holder, 10, and thus lock the valve against any material opening movement. If the cage be thus displaced before the bottle is emptied of its 20 contents, the failure of the liquid to flow out freely when the bottle is inverted, will at once lead to detection of the fact that the mechanism has been tampered with.

25 The angle at which the bottle must be held to pour therefrom is determined by the inclination of the shoulder-portion, 2, of the bottle.

30 To enable the valve to freely open, the bottle must be tipped or inverted until the lower side of its shoulder-portion, 2, inclines downward toward the valve-seat. The weight, 6, being swiveled to the valve, will always rest upon the lower side of the shoulder-portion, 2, when the bottle is tipped or partly inverted.

35 What we claim as new and desire to secure by Letters Patent is—

1. The combination with a bottle having in its neck a valve-chamber and a valve-seat; of a valve movable in said valve-chamber and adapted to occupy said seat; a cage-holder sealed in the neck of the bottle outside of said valve-chamber; and an apertured cage frictionally supported in said holder and adapted when displaced therefrom to 45 substantially fill the valve-chamber.

2. The combination with a bottle having in its neck a valve-chamber, a valve-seat, and a seat outside of said valve-chamber; of a valve movable in said valve-chamber and adapted to occupy said seat; a cage-holder

adapted to engage said seat outside of said valve-chamber, and having an outwardly projecting hollow stem; an apertured cage frictionally held in said holder and adapted when displaced therefrom to substantially 55 fill said valve-chamber; a peripherally grooved tapered washer inclosing said stem; and a body of cement filling the space between said washer and the neck of the bottle, said neck being provided with an interior groove to receive said cement.

3. The combination with a bottle having in its neck a valve-chamber, a valve-seat, and a seat outside of said valve-chamber; of a valve movable in said chamber adapted to 65 occupy said seat; a cage-holder adapted to engage said seat outside of said valve-chamber, and having an outwardly projecting stem provided with lateral openings; a cage frictionally held in said holder and provided 70 with lateral openings communicating with the valve-chamber; a screen-tube extending from the bottom of said cage up into said stem; and a retainer for the cage-holder sealed within the neck of the bottle. 75

4. The combination with a bottle having in its neck a valve-chamber, a valve-seat, and a seat outside of said valve-chamber; of a valve movable in said chamber adapted to occupy said seat; a cage-holder having a 80 hollow undercut body adapted to engage said seat outside of said valve-chamber, and having an outwardly projecting stem; means for sealing said cage-holder within the neck of the bottle; and a cage insertible within 85 said holder and having spring-tongues adapted to engage the interior of the undercut body of said holder to frictionally retain the cage within the holder, said cage, when displaced from said holder, being adapted 90 to substantially fill said valve-chamber.

In testimony whereof, we have hereunto set our hands this 19th day of February, 1912.

FRANK SMITH.
JAMES T. CLABBY.
